TEMPERATURE CONTROL APPARATUS

Alfred F. Schumann, Lower Merion, Pa., and Alexander J. Turpin, Stewart Manor, N. Y., assignors to Hauck Manufacturing Company, Brooklyn, N. Y., a corporation of New York

Application April 15, 1943, Serial No. 483,118

1 Claim. (Cl. 236—15)

The invention relates to the control of the temperature prevailing within a combustion chamber, more especially to a chamber fired by a suitable burner nozzle discharging thereinto. In the operation of heating chambers of this nature, there is a tendency for the temperature of the interior of said chamber, or of a chamber or vessel indirectly heated therefrom, to overrun a predetermined maximum, notwithstanding the fact that the burner element has been turned down completely or to the limit of its minimum regulation.

The present invention has for an object to afford means whereby, when the burner control reaches its minimum limit of regulation, a further control is brought into operation by which a cooling medium is automatically applied to reduce the temperature the desired extent.

A further object of the invention is to provide an automatic control means which will effect regulation as well of the burner, the aforesaid cooling medium applying means being maintained ineffective until such time as a burner operating means has attained its minimum limit position.

In carrying out the invention, a suitable burner is provided for discharge into a combustion chamber, said burner being provided with the usual or special means for regulating the volume of combustible consumed by the burner between a maximum and a minimum value. In addition, provision is made for cooling as in providing the chamber with an admission opening for a gaseous cooling medium such as air, which opening is designed to be controlled for regulation of the volume of admitted air.

In accordance with the invention, there is associated with the aforesaid burner regulator means and with the means for controlling admission of air or like gaseous medium, a temperature responsive element and motor means controlled thereby, said motor means being designed to operate a pulley system. The latter, in turn, is connected with the operating element of the burner and also with the means for controlling the cooling medium, for example, a closure door or damper for the opening to the chamber. The pulley system to this end includes a movable pulley unit flexibly connected with the motor means for reciprocation thereby, said movable pulley having a cable running thereover, one end of which is connected over a fixed pulley to a predetermined mass and the other end over a second fixed pulley to a greater mass, both being suspended from the cable. The first-named connecting portion of the cable also is attached to

the burner operating element to cause the same to move angularly in the regulation of the burner in accordance with the reciprocation of the cable portion, while the second-named connecting portion of the cable is attached to regulating means for the cooling medium, for example, to cause said medium to be applied or interrupted in accordance with the reciprocation of said last-named cable portion. Due to the relation of the two masses attached to the said respective ends of the cable portion, the lighter mass will be the first to rise with movement of the movable pulley unit as the motor means operates under the influence of the temperature-responsive element in a direction to reduce the volume of combustible from the burner. When this combustible regulation attains a position for minimum supply of combustible, stop means will be engaged which will prevent further movement of the burner operating element in a direction to reduce volume of combustible.

The lesser mass will therefore no longer be elevated and continued pull on the pulley unit by the motor means will cause the heavier mass to rise, thereby operating the means regulating the cooling medium sufficiently to reduce the temperature such that the responsive element actuating the motor means will cause the latter to reverse the direction of movement of the movable pulley unit.

The nature of the invention, however, will best be understood when described in connection with the accompanying drawings, in which:

Fig. 1 is a fragmentary front elevation of a heating chamber with attached burner and air-admission door, together with the automatically operating means for regulating the operation of said burner and air-admission door.

Fig. 2 is a fragmentary longitudinal section of the heating chamber and air-admission door, with burner shown in elevation and the automatically operating means omitted.

Fig. 3 is a perspective view indicating more or less diagrammatically the automatically operating means in position of maximum volume of combustible supply to the burner.

Fig. 4 is a similar view with the various elements in their respective locations for operation of the burner under minimum supply of combustible, while Fig. 5 illustrates similarly the elements in their respective locations for operation of the burner under minimum supply of combustible and with introduction of a cooling gaseous medium.

Referring to the drawings, more especially Figs. 1 and 2, 10 designates a suitable combustion

chamber whose temperature it is desired to maintain at a predetermined maximum value or through it the temperature of a mixture or bath 11 in a vessel 12 through a pair of communicating pipe coils 13 and 14 respectively in the combustion chamber 10 and the vessel 12. The combustion chamber is heated by discharging thereinto the products of combustion and/or flame of a burner 15 of any well-known or special construction designed for variation, between limits, of the volume of combustible. Such a burner may, for example, be of the nature of the proportional burner set forth in U. S. Letters Patent Nos. 2,219,119 and 2,290,785 granted applicants' assignee. Burners of this nature are operated for regulation of the volume of combustible supply usually through the oscillation of an angularly movable element or arm 16 between two positions as determined by suitable stops or lugs 17 and 18, respectively, the former being that for maximum supply of the combustible and the latter that for minimum supply thereof, all of which is well understood and forms no particular part of the present invention.

Provision is made, however, to further control the temperature of the combustion chamber and/or the coil 13 therein by the introduction of a cooling medium, in the particular embodiment atmospheric air, which is introduced through an opening 19 located, for example, below the burner. The location of this opening, however, may be varied to suit the particular conditions and various constructions of heating chambers. Normally, opening 19 is designed to be closed by a door 20 hinged at 21 so as to be capable of swinging outwardly to afford various areas of opening for the introduction of air into the interior of the chamber 10.

It will be understood that during the normal operation of the heating chamber, door 20 will remain in its position to close the opening 19 and the regulation of the temperature within the heating chamber 10 will be effected solely by properly positioning the element 16.

In accordance with the invention, this is to be accomplished automatically and by the same mechanism whereby further regulation (lowering) of the temperature is attained should the control effected by movement of the element 16 be insufficient to hold the temperature to the predetermined maximum when element 16 has reached its minimum regulating position. This necessitates, in the first place, a control system subject to the temperature prevailing within chamber 10, or, in the case of the embodiment herein described, the temperature of the bath 11, which system may comprise a heat-responsive member as a thermocouple 25. The thermocouple in turn being responsive to such temperature, is caused to actuate through a suitable controller means 26, as is well understood, a motor means 27 which is connected, as hereinafter set forth, through a pulley system, with the element 16 and also with a bracket 28 extending outwardly from the door 20.

The pulley system for securing this connection to the two regulating elements for control of the temperature includes a movable pulley unit 30 which is connected flexibly as by means of a cable or the like 31 to the oscillatable arm 32 of the motor means 27, said arm being angularly movable under the influence of the controller 26. Pulley unit 30 is connected by a further cable running over said pulley to a weight 33 of predetermined mass, suspended by this cable portion

34 at its one end; and the other end of said cable is connected to a second weight 35 of a somewhat greater mass suspended by cable portion 36, the one portion 34 of the cable connected to weight 33 running over fixed pulleys 37 and 38, 38' and the other portion 36 of the cable running over a fixed pulley 40.

The operation of the control system is indicated in the diagrammatic representations, Figs. 3 to 5. Fig. 3 illustrates the location of the various members at normal operation with maximum supply of combustible to the burner 15, the regulating arm 16 thereof being then in its extreme left-hand position as limited by the lug or stop 17. When the temperature within the vessel 12 attains the desired predetermined value, or the temperature suddenly rises, in the case of an exothermic reaction occurring in connection with the heating of a mixture, the temperature control hereinbefore described will operate in manner well understood to move said arm toward the minimum position through the cable connections which connect it to the arm 32 of the controller system. Weight 33 is elevated thereby, allowing of this angular movement of arm 16, but the weight 35, being of greater mass, will retain its position. This continues until arm 16 engages the lug or stop 18, and if this reduction in supply of combustible is insufficient to reduce the interior temperature of chamber 10 to the required degree, it will be apparent that other means must be provided to effect a reduction as the burner is of the continuously operating type with no shut-off at minimum regulating positions, thus avoiding the necessity for ignition controls and the like.

In Fig. 4 this minimum position of the regulating arm 16 is indicated and it will be noted that the weight 35 still retains its position and that the weight 33 has been elevated a corresponding distance, indicated at (a), above the position for maximum supply of combustible.

By the time arm 16 assumes its position of minimum regulation, further operation of the controller arm 32 in the direction for reduction of temperature will begin to elevate the weight 35. This results from the fact that arm 16, in engaging with the stop 18, introduces an infinite resistance with respect to the weight 33 whereby the continued pull on pulley 30 takes effect on the portion 36 of the cable and causes weight 35 to rise to the extent of the travel of said pulley 30. The extent of this elevation is indicated at (b), Fig. 5, and the cable portion 36, being connected with the closure member 20, moves the same about the hinge 21 to uncover the opening 19 and allow atmospheric air to be introduced therethrough to the interior of chamber 10 and effect the required cooling.

We claim:

The combination with a heating chamber having a burner for fluid combustible discharging thereinto, said burner being provided with control means for regulating the volume of combustible and including stops to limit said means between a maximum and a minimum operating value, the said chamber having also an opening for admission of a cooling medium, together with control means for regulating the area of said opening; of means for operating the two said control means of the said chamber, comprising a temperature-responsive element and motor means controlled thereby, and a pulley system including a movable pulley connected with the

motor means to be reciprocated thereby, together with a cable running over the movable pulley, one portion thereof passing over a fixed pulley and having suspended from its end a predetermined mass and the other portion passing over a second fixed pulley and having suspended from its end a greater mass, said first-named connecting portion of the cable being connected with the burner control means and the second-named connecting portion with the cooling medium ad-

mission means, whereby when the burner means attains the limit stop for minimum volume of combustible, the lesser mass ceases to follow the movement of the movable pulley and remains stationary with continued movement of said movable pulley while the greater mass will follow said movement and will accordingly operate the cooling medium admission means.

ALFRED F. SCHUMANN.
